UNITED STATES PATENT OFFICE

1,920,902

MACHINE FOR MAKING PADS FOR SOCK HOLDERS

Jacob Goldschmidt, Dusseldorf, Germany

Application August 9, 1929, Serial No. 384,754, and
in Germany October 17, 1927

1. Claim. (Cl. 223—15)

My invention relates to a machine for finishing blanks into pads for sock holders.

It is an object of my invention to facilitate the manufacture, and to improve the quality, of such pads.

To this end, I so design my machine that the pad is finished by folding over its edges without requiring a templet. The edges are folded down directly on the body of the blank.

10 It has already been proposed to fold the edges of a blank about a templet, and to strip the folded blank from the templet. By dispensing with the templet, I obtain more clearly defined edges in the blank.

15 Preferably the edges are folded twice which improves the appearance and increases the life of the finished article.

The pad is that part of a sock holder to which the leg bands and the strap are attached. Heretofore the edges of the pad were folded down by hand or by means of the templet aforesaid. Folding by hand is tedious and inaccurate, and the drawbacks of the folding about a templet have already been set out.

20 25 The pads are made of suitable material, such as satin, with or without a lining of gauze, paper or the like.

The machine according to my invention is substantially a press having die heads, dies and folders, and, if desired, means for heating any or all of the folders and die heads, for instance, by electric resistance heaters.

30 35 The means for operating the press will not be described as they are of the usual type, cams, levers, etc., which will be obvious to any expert.

In the accompanying drawings a machine according to my invention and the stages of its operation, are illustrated by way of example.

40 In the drawings Fig. 1 is a section of the machine on the axis of its die heads and dies.

Fig. 2 is a plan view of the upper die, with its folders,

45 Fig. 3 is a section on the line 3—3 in Fig. 2,

Fig. 4 is a plan view of the lower die, with its folders,

Fig. 5 is a sectional elevation of the upper die head;

50 Fig. 6 is a side elevation of the die head; Fig. 7 is a plan view of the upper die head, showing a plunger which is fitted to slide in the die head,

Figs. 8 to 12 illustrate various stages of the manufacture of the pad.

55 Fig. 13 is a sectional plan view of the die head, the feed slide and the dies,

Fig. 14 is a section on the line XIV—XIV in Fig. 13, with the die head in its initial position,

Fig. 15 is a similar section, with the die head in its final position with respect to the hole in the feed slide,

60 Fig. 16 is a section on the line XVI—XVI in Fig. 13, showing the folding-down of the blank corners, and

Fig. 17 is a similar section, showing the first stage of the final folding operation.

65 The blank *a*, as punched, is shown in Fig. 8. The line along which the four edges or corners *e* and the edge strip *f*, are folded down, are shown dotted. *b* are incisions in the sides of the blank.

70 *c*, Figs 1 and 13 to 15, is a feed slide which is presented to the die head *d*. The feed slide *c* has shoulders *q*, *q* for supporting the edges or corners *e*, *e*, and a strip or ledge *q'* for supporting the edge strip *f*. The relative size and shape of the die head *d* and the hole *p* in the feed slide *c* will appear from Fig. 13.

75 The blank *a* is placed on the feed slide *c* as shown in Fig. 14, with its corners bearing on the shoulders *q* and the edge strip *f* bearing on the ledge *q'*. The die head *d* is now lowered as shown in Fig. 15 and moves through the hole *p*, folding up triangular flaps of the blank at *e*, and a substantially rectangular flap at *f*, Fig. 9.

80 The die head, with the blank in this condition, is now lowered to the top of the upper die *v*, Fig. 16. The upper die has folders *i*, as will be described in detail with reference to Fig. 2, and retaining springs *g* in the shape of the letter V inverted. The folders *i* advance and turn down the triangular flaps *e* and the rectangular flap *f*, as shown. The blank is now as shown in

85 Fig. 10. The springs *g* are forced aside by the descending die head *d* and return when the die head ascends, holding the blank when the die re-ascends.

90 The folders *i* remain in their advanced position while the die head re-lowers and, moving through the hole in the upper die *v* which corresponds to its contour, attains the lower die *w* together with the blank. While the blank moves through the upper die *v*, the portions having the folded-over corners *e* are erected, as shown in Figs. 11 and 17. At the same time, the portions having the incisions *b* are erected, as also shown in the said figures. The upper die head *d*, as will appear from Fig. 13, has a clearance with respect to the opening in the upper die *v* which corresponds to the thickness of the erected portions, and so the die head moves through the die *v* with the blank.

110

The die head *d* is hollow and a plunger *k* is mounted to slide in it. When the blank is in the position Fig. 17, the die head *d* ascends while the plunger *k* is advanced by means which will be described. At the same time, a lower die head *o* is moved up into the hole of the die *w* to meet the plunger *k*. Folders *n* are now advanced by means to be described which, being heated electrically, fold over and iron the edges of the blank. The lower die head *o* may also be heated electrically. The blank is now finished, Fig. 12, and is removed by the descending lower die head *o*.

The leg bands, not shown, are attached at the two side edges *e*—*e*, and the strap, not shown, is attached at the central edge *f*.

Referring now to Figs. 5 and 6, *k* is a plunger which is mounted to slide in the upper die head *d*, *u* is a push rod at the upper end of the plunger *k*, *s* is a yoke on the rod *u*, *r* are three rods extending upwardly from the plunger *k* through bores in the die head *d* and in the yoke *s*, and *t* are springs on the rods which are inserted between the upper face of the die head *d* and the yoke *s*.

Reference character *l* is a lever adapted to exert thrust on the push bar *u* when it is desired to force the plunger *k* out of the die head *d*.

The folders are illustrated in Figs. 2 and 4, with the means for operating them. In the upper die *v*, two folders are provided for each corner at *e*, making four, and a fifth folder handles the flap at *f*. The folders are guided between rollers on the face of the die, and are supported by a ring *h*. Each folder *i* is slotted at *x*, the slots extending at an angle to the

longitudinal axis of the folders, and a pin *y* is secured on the ring for engaging each of the slots *x*. A handle *z* serves for rotating the ring *h* to advance or retract the folders.

A similar arrangement, but with four folders *n* only, and an operating ring *m*, is provided for the lower die *w*, Fig. 4.

g are springs, of inverted V-shape, which are secured on the upper die *v*, Fig. 3, for retaining the blank when the upper die head has been retracted.

The folders *n* on the lower die may be heated electrically, and so may be the lower die head *o*, in order to "iron" the pad during the last stage.

I claim:

In a machine for finishing blank into pads for sock holders, erecting dies having holes adapted to retain certain marginal portions of the blank, an upper die head adapted to move through said holes with the blank for erecting the retained marginal portions of the blank, means on the last erecting die for folding the erected portions down onto the body of the blank, a plunger on said upper die head, means for advancing said plunger beyond the upper die head, a finishing die having a hole of larger area than said plunger, a lower die head adapted to enter the hole in the finishing die in the opposite direction to the movement of said plunger, the blank being engaged between said plunger and the hole in said lower die head; and means on said finishing die for folding over the erected portions of the blank down onto the body of the blank in the clearance between said plunger and the hole in said finishing die.

JACOB GOLDSCHMIDT.
